CHARLES H. W. NASON, OF NEW YORK, N. Y., ASSIGNOR TO JENKINS TELEVISION CORPORATION, OF JERSEY CITY, NEW JERSEY, A CORPORATION OF DELAWARE

ELECTROOPTICAL TRANSLATION SYSTEM

Application filed February 10, 1930. Serial No. 427,272.

This invention relates to electro-optical systems, and with particularity to methods and means for translating light variations into electric signals.

5 The invention has for one of its objects to provide a method of modulating a carrier current by light signals.

Another object of the invention relates to a method and means for translating light 10 and shade characteristics into corresponding electric currents having a restricted frequency spectrum.

A further object is to provide a method of 15 modulating the amplitude of a carrier-wave by variations in photo-electric response having quasi-capacitance effect.

Another feature of the invention relates to a method of analyzing and translating the shade characteristics of an object, image or 20 visual representation into corresponding electric currents.

Another feature of the invention relates to a novel method of employing photo-electric variations to control the resonance characteristic of an oscillatory circuit supplied from a source of carrier current. As a result of 25 this latter feature the frequency spectrum of the transmitted carrier waves is substantially independent of the frequency variations of the light impulses incident upon the light 30 sensitive device.

Other features and advantages not specifically enumerated will be apparent after a consideration of the following description and the appended claims.

35 In the drawings, Fig. 1 shows one preferred manner of utilizing photo-electric variations to control the resonance characteristics of a transmission circuit;

40 Fig. 2 shows schematically how the amplitude of a carrier wave is varied according to the invention.

While the invention will be described in connection with a television system it will be understood that the novel features are capable of use in any system requiring electro-optical translation such as picture transmission, telegraphy, sound and other recording systems. Furthermore, while the invention 50 is shown as embodied in a television system

employing one particular form and arrangement of apparatus, it will be understood that the invention is not limited thereto. Accordingly the numeral 1 represents a well known type of television scanning device in the form of a disc having a series of perforations or scanning elements therein. When the object to be scanned is a continuously moving film or the like, as indicated in the drawing by the numeral 2, then these scanning perforations are arranged at equal radial distances from the axis of rotation of member 1. If desired these scanning elements may be arranged in spiral sequence as disclosed in U. S. Patent No. 1,679,086 to C. F. Jenkins. However, it is preferred to employ an arrangement such as disclosed in the copending application of C. H. W. Nason, Serial No. 418,205, filed January 3, 1930. Positioned on one side of disc 1, which is rotated at the requisite speed from any suitable motive source (not shown), is a source of light 3, preferably of high and constant intensity such as an arc lamp. By means of a suitable optical system, represented schematically by numeral 4, the light from source 3 is projected on the scanning disc 1. Consequently as the disc is rotated the film 2 is illuminated in successive parallel strips across the width of the film. The light passing through each elemental area of the film is projected upon the photo-electric cell, preferably of the Elster-Geitel type, comprising a light-sensitive electrode or coating 6, and another electrode 7. It has been found by actual measurement that the electro-static capacity of such a cell undergoes variations in value as the coating is subjected to different degrees of illumination.

The electrodes of cell 5 are connected across an inductance 8 to form therewith an oscillatory circuit. This oscillatory circuit is preferably designed to have a relatively sharp resonance curve at the frequency of the carrier from source 9. For this purpose the inductance 8 may constitute the secondary of a high frequency transformer the primary of which is coupled to the carrier source 9. If desired the oscillatory circuit 100

may include a condenser 10 to supplement the electro-static capacity of the cell 5.

Referring to Fig. 2 there is shown diagrammatically in curve A the resonance characteristic of the circuit including the photo-cell 5 and the inductance 8. The abscissæ in Fig. 2 represent values of capacity, while the ordinates represent percentage resonance or amplitude of the carrier flowing in the 10 tuned circuit. In order that there may be a proper and uniform relation between the amount of light incident upon the cell 5 and the amplitude of the carrier, it is preferred to design the constants of the oscillatory or 15 tuned circuit so that the variations in capacity due to the cell 5, cause the amplitude of the carrier to vary between the points *a* *b* of the resonance curve or any other linear portion of said curve. In other words the 20 values of capacity and inductance in the tuned circuit are preferably so designed that when the maximum light falls on cell 5 the capacity of the tuned circuit has the value *C*, and when the cell is dark the capacity of the 25 tuned circuit has the value *d*, consequently the amplitude of the carrier will vary as indicated by the curve B, and these variations in amplitude will correspond to the variations in shade of the elemental areas of film 2. 30 These varying carrier waves may then be impressed upon a broadly tuned radio-frequency amplifier of any well known type as indicated by the numeral 11. This amplified carrier having amplitude variations corresponding to the shade characteristics of film 1, may be transmitted by any suitable radio 35 transmission apparatus or system. If it is desired to obtain a current corresponding to the amplitude variations merely, then the 40 modulated carrier after being amplified by device 11, may be detected or demodulated by any well known demodulating device indicated by numeral 13, this demodulator being tuned by the condenser 14 to the frequency 45 of the carrier source 9. This demodulated signal may be further amplified by device 15 and may be transmitted by any suitable transmission system, or it may be employed to operate a suitable reproducing 50 device such as a glow discharge lamp at a receiving station. In this latter case the reproducing lamp will, of course, be provided with an integrating scanner similar to the scanner 1, and rotated in synchronism therewith.

While the invention has been described in connection with certain specific apparatus and systems, it will be understood that the idea of utilizing the variations in capacitance 60 of a photo-cell to control a tuned circuit or other similar capacitance responsive arrangement is capable of use in many other systems than that specifically disclosed.

While the above description premised on 65 the variation in what has been termed "elec-

tro-static" capacity changes in a photo-sensitive cell, it will be understood that the invention is not limited to any particular theory as to the manner in which the photo-cell controls the "tuning" of the resonant or oscillatory circuit. Accordingly the term photo-capacitance variation as employed in the claims is intended to cover that variation in a photo-electric cell which appears to correspond to electro-static variations.

What is claimed is:

1. The method of signalling employing a carrier current which comprises translating the signals into corresponding light variations, varying the capacitance of a photo-electric cell in accordance with said light variations, and employing said capacitance variations to control the resonance of an oscillatory circuit sharply tuned to resonance at the carrier frequency.

2. The method of signalling employing a carrier wave which comprises translating the signals into variations in capacitance of a photo-sensitive device, and employing said variations to control tuning of a circuit sharply tuned to resonance at the carrier frequency.

3. The method of signalling which comprises translating the signals into photo-capacitance variations, impressing carrier waves on a tunable circuit normally tuned to sharp resonance at the carrier frequency, and using said variations to control the tuning of said circuit.

4. The method of transmitting image characteristics which comprises producing light impulses corresponding to elemental areas of the image to be transmitted, impressing carrier waves on an oscillatory circuit sharply tuned to resonance at the carrier frequency, translating said light impulses into photo-capacitance variations, and employing said photo-capacitance variations to control the tuning of said oscillatory circuit.

5. In a signalling system employing a carrier wave the combination of a source of light variations, means for translating said variations into photo-capacitance variations, and a tuned circuit controlled by said photo-capacitance variations, said circuit being sharply tuned to resonance at the carrier frequency.

6. In a signalling system the combination of a source of light variations, means for translating said variations into photo-capacitance variations, a source of carrier current, and means including said translating means and a circuit sharply tuned to resonance at the carrier frequency for varying the amplitude of said current.

7. In a signalling system the combination of a source of carrier waves, a tuned circuit sharply tuned to resonance at the carrier frequency upon which said waves are impressed, and a variable capacity connected

across said tuned circuit, said capacity being light controlled.

8. In a signalling system the combination of a source of carrier waves, an amplifier device, a tuned circuit between said source and said device and sharply tuned to resonance at the carrier frequency, a variable photo-capacitance connected across said tuned circuit, and a source of light signals for controlling said photo-capacitance.

9. The method of signalling which comprises impressing carrier waves on a tuned circuit sharply tuned to resonance at the carrier frequency, and employing a photo-sensitive cell to detune said circuit in accordance with signals to be transmitted.

10. The method according to claim 9 in which said circuit is tuned to the frequency of said carrier waves.

20 11. In a television system employing a carrier wave, means for translating the shade characteristics of elemental areas of an image to be transmitted into corresponding light impulses, a photo-sensitive cell adapted to have its capacitance varied by said light impulses, a tuned circuit sharply tuned to resonance at the carrier frequency, a source of carrier waves impressed on said circuit and means including said photo-sensitive cell for detuning said circuit to control the amplitude of the carrier waves impressed thereon.

25 12. In a television system employing a carrier wave, the combination of a scanning device, a photo-electric cell adapted to have its capacitance varied under control of said device, a tuned circuit sharply tuned to resonance at the carrier frequency, and adapted to be detuned by said photo-electric 40 cell to control the amplitude of a carrier wave, and means for amplifying the waves passed by said detuned circuit.

13. A system according to claim 12 in which means are provided for demodulating 45 the modulated carrier waves passed by said tuned circuit, and a light source controlled by said demodulated waves.

In testimony whereof I have hereunto set my hand on this 31st day of January, A. D. 50 1930.

CHARLES H. W. NASON.
